UNITED STATES PATENT OFFICE

GEORGE A. KOHOUT, OF CHICAGO, ILLINOIS

GRATE CONTROL

Application filed January 27, 1932. Serial No. 589,078.

My invention relates to the control of the grates of a stoker and is particularly applicable to that type of furnace in which the grates are so constructed that by rocking them they gradually move the fuel back from the forward end of the furnace.

In my application Serial No. 302,395, filed August 27, 1928, I show a grate control mechanism by which a periodic rocking of the 10 grates is accomplished from a drive shaft that is continuously rocking to and fro.

It is a purpose of the present invention to provide a grate control mechanism of this character with means for causing a temporary connection between the rock shaft and the member which communicates the action of the shaft to the grates at any time between the normal periodic operation of the grates.

The advantages of this improvement lie 20 in the fact that it enables the furnace operator to manually cause an additional shaking of the grates if at any time the fire appears to need it without the necessity of changing the normal operation of the system. As for example, the operator may notice that the fuel has piled up too much at the front of one furnace and in expecting an immediate demand on the load he may cause the grates to rock a few times extra in order 30 to work this fuel down over the fuel bed to obtain a hot fire before the anticipated demand depletes the supply of steam.

Other examples of the utility of this improvement could be given, but they are believed to be unnecessary.

I will describe the preferred form of my invention by reference to the accompanying drawings wherein—

40 Fig. 1 is a longitudinal section through the furnace illustrating the grate bars in their operative connection to the grate shaking mechanism;

45 Fig. 2 is an end view of the grate shaking unit which is mounted upon the rock shaft;

Fig. 3 is a front view of the same unit; and

Fig. 4 is a partial section on the line 4—4 of Fig. 3.

Referring now in detail to the drawings, 50 the numeral 5 indicates generally the grates which are of the eccentrically pivoted type connected together by means of a bar 6 which in turn is connected with the operating bar 7 that leads to a member 8 forming 55 part of the unit 9 which is operated by the rock shaft 10.

The ash dump grate 11 is not controlled by the rock shaft, but is manually controlled by a bar 12 having a handle 13. The rock 60 shaft 10 may be driven from any suitable source such as for example as a common motor and a crank mechanism as disclosed in my prior application. The only requirement of the present invention is that the shaft rock 65 to and fro. The unit 9 is really a ratchet and pawl mechanism by means of which the rocking motion of the shaft is periodically communicated to the member 8.

The member 14 is secured directly to shaft 70 10 so as to rock therewith by means of a suitable pin 15. This member 14 has at one side the projecting shoulder 16 which is adapted to engage a corresponding shoulder 17 on the member 8 which member is pivoted 75 upon the shaft 10. The member 14 also carries a stub shaft 18 upon which are mounted a plurality of dogs or pawls such as indicated at 19 and 20. The combined cam and ratchet member 21 is rotatably mounted on the shaft 80 10, the teeth on the ratchet wheel 22 thereof being engaged by pawl 19 while the cam member 23 thereof has a cut-away portion as indicated at 24 and is otherwise substantially circular so that the pawl 20 can only drop 85 down from the position shown in Fig. 2 into the cut-away portion 24 when the portion 24 happens to be aligned with the pawl 20.

A holding pawl indicated at 25 at the bottom of Fig. 2 is mounted on the bracket 4 90

which connects the shaft bearing to the furnace wall, and this holding pawl prevents the ratchet wheel 22 from turning backwards. Also, in order to limit the movement of the 5 ratchet wheel in response to the angular movement of the pawl 19, this pawl, as shown in Fig. 3, is wider than ratchet wheel 22 and laps over onto the member 26 which, as shown most clearly in Fig. 2, holds the pawl 19 away 10 from the ratchet wheel 22 during a portion of its movement. This member 26 is adjustable as described in my prior application, but the details of this adjustment are of no importance to the present application and will 15 not be further described. It is believed to be sufficient for the purposes of this invention to point out merely that the member 26 is pivoted upon the shaft 10 and is held in any desired position by means of the lug 27 there- 20 on carrying a pin 28 which engages the teeth 29 on the member 30 projecting out from the bracket 4.

The member 8, as pointed out, has the projection 17 thereon adapted to engage with the 25 shoulder 16 on the member 14 so that, as the member 14 moves in a counterclockwise direction, the member 8 will be forced to move therewith to the full extent of the movement of the member 14. The extent of this movement is adjusted so that it brings the grate substantially level, and, as there is no variation in this movement, the grates are always brought to level position at the end of each shaking motion imparted thereto by the shaft. 30

35 The normal operation of the pawl 20, whenever the depression 24 in cam 23 is positioned under it, is to periodically drop down and abut the shoulder 31 provided on that portion of member 8 which passes around the shaft. 40 10. When this occurs, of course, the member 8 is caused to move with the member 14 and shaft 10 to the limit of the shaft's movement in this direction. This is one complete rocking of the grates to raised position, and, upon 45 the return rocking movement of the shaft, the member 8 is brought back to its original position by means of the shoulder 16 and member 17.

On the next rocking movement of the shaft 50 10, however, the cam 23 will have moved far enough to bring the slot 24 past the pawl 20 so that it cannot drop in the position to again actuate the grates.

In this fashion, a number of rocking movements of the shaft 10 take place for each 55 operation of the grates, and thus, by regulating the periodic operation of the grates, the furnace can be automatically controlled so as to feed the fuel at the proper rate.

60 Having once accomplished this, however, if a temporary shaking of the grates is desired, I provide the novel improvement which is the subject matter of this application.

65 This improvement consists of an auxiliary pawl 32 which is carried on pawl 20 and

pivoted to the same shaft 10. The pawl 20 has within it a bore 33 (see Fig. 4), and a pin 34 carried by the auxiliary pawl 32 extends into this bore and is normally held in one position therein by means of the spring 35. The slot 36 in the side of the pawl 20 permits this pin, which is rigid with the auxiliary pawl 32, to be moved against the pressure of the spring 35 so as to advance pawl 32 toward the shaft 10 beyond the edge 70 of the pawl 20 when the pawl 20 is riding upon the raised portion of the cam 23. A suitable handle 37 is provided for pressing the pawl 32 forward to engage against the shoulder 31 in the manner just described. 75

Now it is believed to be clear that, when the pawl 32 is pushed down into the position shown in Fig. 2, it will upon the movement of the shaft 10 in a clockwise direction engage the shoulder 31 and move the member 8 with the shaft 10 so as to rock the grates in the usual fashion. Members 16 and 17 will return the grates to level position upon the return movement of the shaft 10. In this fashion, the grates may be actuated by temporarily depressing pawl 32 at any time between the normal periodic actuations. 85

90 From the above description, it is believed that the construction and operation of this device will be clear to those skilled in this art and the advantages thereof readily apparent. It is also believed to be obvious that various minor modifications may be made without departing from the scope of the invention as defined in the following claims. 95

Having thus described one specific form 100 of my invention, what I claim as new and desire to secure by Letters Patent is:

1. In a grate shaking device for shaking furnace grates having a member operatively connected to the grates, a rocking drive shaft and mechanism interconnecting said member and shaft for periodically connecting said member to said shaft during a rocking movement of said shaft whereby to move said member and shake the grates, means for causing temporary connection between said shaft and member between the periodical connections thereof whereby to impart an additional shaking to the grates, said means comprising a shoulder on said member, a pawl movable with said shaft but having means yieldingly holding it clear of said shoulder, and means for holding said pawl against said shoulder. 105

110 2. In a grate rocking device for shaking stoker grates having a rocking shaft, a member operatively connected to the grates, and a ratchet and pawl mechanism connecting said shaft and member for periodically causing said shaft to move the member to thereby rock the grates, manually operable means for connecting said shaft and member together at any time between the periodical 115 120 125 130

connections thereof by said ratchet and pawl mechanism whereby to rock the grates intermediate their periodical rocking, said manually operable means being carried by said 5 ratchet and pawl mechanism, and comprising a connecting pawl, a spring for holding said pawl in raised position, and a handle on said connecting pawl for depressing it.

In witness whereof, I hereunto subscribe 10 my name this 15th day of January, A. D., 1932.

GEORGE A. KOHOUT.
